UNITED STATES PATENT OFFICE.

SHERMAN A. BATES, OF COLLINS, IOWA.

AUTOMOBILE-RADIATOR.

1,368,098.

Specification of Letters Patent.

Patented Feb. 8, 1921.

Application filed May 12, 1917. Serial No. 168,245.

To all whom it may concern:

Be it known that I, SHERMAN A. BATES, a citizen of the United States, residing at Collins, in the county of Story and State of Iowa, have invented a new and useful Automobile-Radiator, of which the following is a specification.

The device forming the subject matter of this application is a radiator of that general type used on motor propelled vehicles, and one object of the invention is to provide novel means whereby a thorough cooling of the water in the radiator will be brought about, novel means being provided for securing a circulation of the water about the cooling flues.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—

Figure 1 shows in vertical transverse section, a radiator constructed in accordance with the present invention;

Fig. 2 is a cross section showing the means whereby the flues are mounted in the front and rear walls of the radiator.

The radiator forming the subject matter of this application includes a front 1, a back 2, an end wall 3, and an end wall 4. Extended through the front 1 and the back 2 are flues 5. Each flue 5 has at its forward end a flange 6, and interposed between the flange 6 and the front 1 is a packing washer 7. A packing washer 8 is carried by the rear end of the flue 5 and coöperates with the rear wall 2 of the radiator. A metallic washer 9 may be placed against the packing washer 8, the washer 9 being adapted to receive one end of a compression spring 10. A nut 11 is threaded onto the rear end of the flue 5 and constitutes means for tightening up the spring 10. The construction, obvi-

ously, is such that the front 1 and the back 50 2 of the radiator may expand and contract with respect to the flues 5.

The flues 5 are disposed in lines extended transversely of the radiator. Projecting from the end 4 are baffle plates 12, and projecting from the end 3 are baffle plates 14. The baffle plates 12 are spaced as shown at 15 from the end 3, and the baffle plates 14 are spaced as shown at 16 from the end 4, the baffle plates 12 and 14, therefore, projecting, alternately, from the ends 3 and 4. The baffle plates lie between the lines of flues 5. The baffle plates 12 and 14 preferably extend between the front 1 and the back 2, and the front and the back have 65 projections 50 whereon the baffle plates are supported.

In practical operation, air passes through the flues 5, and the water in the radiator is compelled, by the baffle plates 12 and 14, to 70 travel in a zigzag line about the flues, as will be understood readily when Fig. 1 of the drawings is examined.

The general construction of the radiator is such that the water will be cooled adequately and thoroughly, and, at the same time, owing to the structure shown in Fig. 2, the necessary expansion and contraction is possible.

Having thus described the invention, 80 what is claimed is:—

A radiator for use in connection with the internal combustion engine of an automobile, comprising end walls, a back and a front, the back and the front having inwardly extended projections; lines of spaced air thimbles extended between the front and the back and communicating at their forward and rear ends directly with the atmosphere; and baffles located between the 85 lines of thimbles to form a sinuous water passage through the radiator, the baffles projecting, alternately, from the respective end walls, each baffle terminating in closely spaced relation to the end wall opposite to 90 the end wall from which the baffle projects, to form openings the full width of the baffles, the openings being bounded by the ends 95

of the baffles, the end walls, the front and the back, the width of each baffle being equal to the length of those portions of the thimbles which lie between the front and the back, the baffles being supported on the projections, each baffle having a flange coöperating with the front, a spring coöperating with the back, and a nut retaining the spring, the spring permitting expansion, but

serving to retain the baffles on the projections. 10

In testimony that I claim the foregoing as my own, I have hereto affixed my signature in the presence of two witnesses.

SHERMAN A. BATES.
